SHUTTLE THREADING AND TENSIONING DEVICE

Joseph Coldwell, Fall River, Mass., assignor to
John S. Coldwell, Fall River, Mass.

Application July 24, 1943, Serial No. 496,256

8 Claims. (Cl. 139—215)

The present invention relates to textile loom mechanisms and is particularly directed to a threading and tensioning device for shuttles.

Tensioning devices for shuttles in automatic looms heretofore have had no means for regulating or adjusting the tension on the thread to a fine degree as it passes through the shuttle; moreover the heretofore used devices for shuttles on automatic looms have not provided proper tension for different kinds and types of thread, so that all kinds of cloth could not be woven. Heretofore the tensioning and threading devices have provided tension on the thread by passing the thread through labyrinths or around a series of pins so as to create a tortuous path for the thread. Such tensioning devices are normally threaded by hand with the aid of a hook or wire and are therefore not suited to automatic looms, as the ends of the thread must be manually threaded.

The principal object of the present invention is to provide a tensioning and threading device for shuttles for automatic looms whereby the thread from the bobbin automatically threads itself in the shuttle and tensioning device.

A further object of the invention is to provide means for regulating the tension upon the thread as it passes through the shuttle.

Another object is to provide a tensioning device which can be quickly threaded without the aid of hooks or wires.

Still another object of my invention is to provide an automatic tensioning device which is simply constructed and which can be inexpensively manufactured and assembled.

Still another object of my invention is to provide a tensioning device for shuttles which is adapted to handle all standard types and sizes of threads.

With the above and other objects and advantageous features in view, the invention consists of a novel arrangement of parts more fully disclosed in the detailed description following, in conjunction with the accompanying drawing, and more specifically defined in the claims appended thereto.

Referring to the drawing:

Fig. 1 is a plan view of the tensioning device installed in the head of a shuttle;

Fig. 2 is a sectional view on line 2 of Fig. 1 with the pallet in its lowest position;

Fig. 3 is a sectional view on line 3 of Fig. 1 showing the pallet in its uppermost position;

Fig. 4 is a plan view with pallet in raised position and showing the thread positioned within the guide openings;

Fig. 5 is a plan view with pallet in lowest position and showing the thread properly threaded in the eyes;

Fig. 6 is a perspective view of the base portion; and

Fig. 7 is a perspective view of the pallet mounted on the swivel pin.

It has been found desirable to provide a tensioning and threading device which eliminates the use of waste, cloth, fur, leather, or similar material positioned to create a drag or friction upon the thread and to provide means to adjustably regulate the tension and which automatically threads itself and the shuttle.

Referring to the drawing reference numeral 10 indicates a shuttle provided with a bobbin 11 for supplying the pick or filling thread 12, the thread

15 leaving the shuttle and sliding in the bottom of the groove 13 and out of the eye 14 formed by pins 15 and 16 interposed therebetween. Along the course of the thread is positioned a tensioning device generally designated as 17, located in

20 the recess 18 of the shuttle 10 and retained firmly in position by machine screws 19 and 20 engaged into threaded holes 21 in the base 22. Extending vertically from said base at right angles thereto is a flange 23 having two upper surfaces 24 and

25 25 disposed so as to form a V shaped opening 26 which is made continuous with a retaining eye 27 by means of a communicating slot 28. A second flange 29 is similar to and spaced from the flange 23 except that it is of greater thickness,

30 with its upper surfaces 30 and 31 similarly disposed to form a V shaped opening 32 which is made continuous with a retaining eye 33 by means of a slot 34. Interposed between the space flanges 23 and 29 is a boss 35 having upper surfaces 36 and 37 forming an opening 38 which is made continuous with a retaining eye 39 by means of a slot 40. The eyes 27, 33 and 39 are in axial alignment and at right angles to the flanges 23

40 and 29, and the slots 28, 34 and 40 are also in the same plane. A hinge pin 41 is positioned in an opening 42 of flange 23 and is secured in flange

45 29 by being threaded at 43, the pin being parallel to the alignment of eyes 27, 33 and 39. A pallet generally designated as 44 is provided, having bearings 45 and 46 by which it is swivelly mounted on the pin 41. Extending at right angles from bearings 45 and 46 are curved arms 47 and 48, which terminate in the loops 49 and 50, the latter

50 being open as indicated at 51 and 52. The axial centers of the loops 49 and 50 describe arcs which pass through the axial center lines of the eyes 27, 33 and 39, the downward motion of the pallet 44 being limited by the loops 49 and 50 making contact with the base 22, and the upward motion

55 being limited by a stop 53 which makes contact with the base at 54. An adjusting pin 55 is snugly fitted into the shaftways 57 and 58 of the shuttle 10, and is provided with a hole 59 through

60 which an elastic cord 60 passes, the elastic cord

being retained by a knot 61. The other end of said elastic cord passes through the hole 62 provided in arm 47 and is retained in position by a knot 63, an opening 64 in the shuttle 10 providing clearance for the elastic cord. The tension of the elastic cord is adjusted and regulated by turning the pin 55 to thus wind or unwind the cord.

The operation of the novel tensioning and threading device may now be explained. First I will explain the operation when the tensioning device is used on shuttles where the bobbins are manually replaced. After the bobbin has been placed in the shuttle it is only necessary for the operator to position the thread 12 of the bobbin in the groove 13a of the shuttle and pull the thread backward toward the bobbin. This action causes the thread to be pulled into the groove 13 and with eye 14 formed by the pins 15 and 16, and simultaneously the friction of the thread leaving the bobbin causes the thread to become taut, and lay in the V shaped openings 26 and 32 and the opening 51 and 52 of the loops 49 and 50. This action also causes the pallet to be depressed to its lowest position and the thread is guided by the V shaped openings 26 and 32 into the slots 28, 34 and 40. The thread as it is pulled from the bobbin has a slipping action as it unwinds from the bobbin spindle which causes it to be securely seated in the eyes 27, 33 and 39. It can now be readily seen that the pallet exerts an upward tension upon the thread 12 and that this tension is minutely and exactly regulated by rotating pin 55 which causes elastic cord 60 to be shortened or lengthened as desired. Although I have described the operation as being done manually, the operation of pulling the thread 12 into the slot 13a and 13 and thence into eye 14 is automatically done on automatic looms by the normal action of the shuttle in conjunction with the usual means provided on automatic looms.

While I have illustrated and described a preferred embodiment of my invention, I wish to have it understood that I do not limit myself to the specific construction and arrangement of parts herein shown and described, but wish to cover all similar or equivalent constructions following within the terms or spirit of appended claims.

What I claim as new and desire to secure by Letters Patent of the United States is:

1. In a threading and tensioning device for a shuttle, a base having spaced standards, said standards having aligned thread retaining eyes, slots communicating with said eyes, guide openings for said slots, whereby a thread may be drawn through said guide openings and said thread retaining eyes, and a thread tensioning device mounted on said base between said spaced standards for engaging the thread passing through the aligned thread retaining eyes.

2. In a threading and tensioning device for a shuttle, a base having spaced standards, said standards having aligned thread retaining eyes, slots communicating with said eyes, guide openings for said slots, whereby a thread may be drawn through said guide openings and said thread retaining eyes, and a thread tensioning device pivotally mounted on said base between said spaced standards for engaging the thread passing through the aligned thread retaining eyes.

3. In a threading and tensioning device for a

shuttle, a base having spaced standards, said standards having aligned thread retaining eyes, slots communicating with said eyes, guide openings for said slots, whereby a thread may be drawn through said guide openings and said thread retaining eyes, and a thread tensioning device pivotally mounted in said base between spaced standards and having loops adapted to receive the thread passing through the aligned thread retaining eyes.

4. In a threading and tensioning device for a shuttle, a base having spaced standards, said standards having aligned thread retaining eyes, slots communicating with said eyes, guide openings for said slots, whereby a thread may be drawn through said guide openings and said thread retaining eyes, and a thread tensioning device pivotally mounted in said base between spaced standards and having loops adapted to receive the thread passing through the aligned thread retaining eyes, said thread tensioning device having a limit stop to prevent excessive rise with respect to said retaining eyes.

5. In a threading and tensioning device for a shuttle, a base having spaced standards, said standards having aligned thread retaining eyes, slots communicating with said eyes, guide openings for said slots, whereby a thread may be drawn through said guide openings and said thread retaining eyes, and a thread tensioning device mounted on said base between said spaced standards for engaging the thread passing through the aligned thread retaining eyes, said thread tensioning device having a limit stop to prevent excessive rise with respect to said retaining eyes.

6. In a threading and tensioning device for a shuttle, a base having spaced standards, said standards having aligned thread retaining eyes, slots of narrow width communicating with said eyes, guide openings for said slots, whereby a thread may be drawn through said guide openings and said thread retaining eyes, and a thread tensioning device mounted on said base between said spaced standards for engaging the thread passing through the aligned thread retaining eyes, said thread tensioning device being resiliently urged upwardly to tension the thread.

7. In a threading and tensioning device for a shuttle, a base having spaced standards, said standards having aligned thread retaining eyes, slots of narrow width communicating with said eyes, guide openings for said slots, whereby a thread may be drawn through said guide openings and said thread retaining eyes, and a thread tensioning device mounted on said base between said spaced standards for engaging the thread passing through the aligned thread retaining eyes, said thread tensioning device being resiliently urged upwardly to tension the thread and means for controlling the tension.

8. In a thread receiving element for a shuttle, comprising a base, spaced vertical standards on said base, said standards having aligned thread retaining eyes, inclined slots communicating with said eyes at one side thereof, and angularly disposed guide surfaces forming a wide inlet for receiving a thread and converging for guiding the thread into the slots.

JOSEPH COLDWELL.
